GIUSEPPE BELLUSCI, OF NEW HAVEN, CONNECTICUT.

EXTENSIBLE TABLE.

1,204,841.

Specification of Letters Patent. Patented Nov. 14, 1916.

Application filed February 19, 1916. Serial No. 79,418.

To all whom it may concern:

Be it known that I, GIUSEPPE BELLUSCI, a subject of the King of Italy, residing at New Haven, in the county of New Haven 5 and State of Connecticut, have invented certain new and useful Improvements in Extensible Tables, of which the following is a specification.

One of the objects of this invention is to 10 provide an extensible table which shall be extremely simple in construction, economical in cost, and thoroughly efficient in operation and durable in use.

A further object is to provide a table of 15 this character which may be extended or contracted with a minimum of manual effort and with a maximum of celerity.

A further object is to provide a table of 20 this character which shall not be bulky, cumbersome, or heavy, but which, on the contrary, shall be light in weight and exceedingly compact.

A further object is to provide an extensible table, the mechanism of which is designed 25 so as to obviate likelihood of its getting out of order.

A further object is to provide an extensible table, the mechanism of which is so simple as readily to be understood by persons 30 of no mechanical ability.

Other objects of specific improvement, going to make up the ultimate perfection of the entire device, will appear as the specification proceeds and the nature of the invention 35 more fully appears.

The invention is graphically portrayed in the accompanying drawings, which disclose 40 illustratory form of embodiment of the invention capable of carrying out the underlying principles thereof.

Like reference-characters denote corresponding parts throughout the several views.

A brief description of the different figures of the drawings may be given as follows:

45 Figure 1 is a bottom plan view of the table in extended position, the bottom cover-plate being shown broken away to more clearly show the interior mechanism, and the table-legs being shown in section; Fig. 2 is a longitudinal section, on the line 2—2, Fig. 1, looking in the direction of the arrows; Fig. 3 is a bottom plan view of the table in its contracted position, the table-legs being shown in section, and the bottom cover-plate 50 being removed for purpose of clearness of illustration of other parts; Fig. 4 is a trans-

verse section, on the line 4—4, Fig. 1, looking in the direction of the arrows; Fig. 5 is a view similar to Fig. 4, but showing a supplemental end-leaf in collapsed, or inactive, 60 position; Fig. 6 is a section on the line 6—6, Fig. 2, looking in the direction of the arrows; Fig. 7 is a fragmentary perspective view of the table-frame; Fig. 8 is a perspective detail view of one of the main table- 65 leaves detached.

Referring, now, in detail to the drawings: The table-frame includes two, longitudinally-extending, vertically-disposed side-bars 1, 1, at the ends of which are the four 70 table legs 2. Each of the side bars is provided, on its rear face, with two, longitudinally-extending grooves 1^a, 1^a in the same horizontal plane, and each extending from a table leg 2 to a point near the longitudinal center of the side-bar 1. The purpose of these grooves will hereinafter appear. Disposed at the bottom of said side-bars 1, 1 and spacing apart the four legs 2 is a bed, comprising two, horizontally- 75 arranged, longitudinally-extending members 3, 3, lateral connecting members 4, 4, and a longitudinally-extending member 5 connecting the bars 4, 4 at the longitudinal center thereof. Guide-strips 6, 6 are carried by the 80 tops of said members 3, 3, at the free edge thereof. The purpose and function of the bed and the guide-strips will appear hereinafter.

Slidable on top of the side-bars 1, 1 is the 90 table top, comprising two, main leaves 7, 7, each of which carries, on its under surface, two angle-portions 8, 8 engaging two of the grooves 1^a in the inner face of the side-bars 1, 1, whereby the main leaves 7, 7 are guided 95 in their sliding movement, and whereby they are held against accidental removal from said side-bars.

Each table-leaf 7 carries, on its under surface, two blocks 10, 10, which are connected by two strips 11, 11. Reciprocable longitudinally of each pair of strips 11, 11 is a slide 12 disposed between said strips and the under surface of the main table-leaves 7, 7, and provided with angled ends 12^a, 105 12^a in juxtaposition to the sides of the strips 11, 11. Each slide 12 carries a boss 13 projecting between the strips 11, 11, and in these two bosses are secured the ends of a suspension-rod 14. Pivoted and slidably 110 supported on this rod 14 are two or more swinging, supplemental table-leaves, each

leaf comprising two sections 15, 16 hinged together, as at 16^a. Conveniently, one of the sections, as 15, carries, a short distance from the hinge-end thereof, straps 17 loosely encircling the rod 14, so as to provide for the pivotal and sliding movement of the supplemental leaves. It will be noted that the member 5 limits downward swinging movement of the table-leaves 15, 16, in the collapsed position thereof.

Horizontally-swinging latches or catches 7^a, 7^b, pivoted at one end thereof, as at 7^b, to the under surface of the main leaves 7, 7, at the inner edge thereof, may be swung beneath the supplemental table-leaves 15—16, 15—16, at the hinge-ends thereof, when said supplemental leaves are in operative position (as shown in Figs. 1 and 2), so as to maintain the two sections 15—16 of each supplemental leaf in the same horizontal plane.

Preferably, two collapsible, supplemental end-leaves are provided, each leaf comprising two sections 18, 19 hinged together, as at 25 20, and these supplemental end-leaves are carried by two sliding carriages having a limited rectilinear movement in opposite directions, and comprising two pairs of vertical side-bars 21, 22, the side-bars of each 30 pair overlapping, as shown, and one of said bars, as 21, being provided with a longitudinally-extending slot 23, in which works a pin 24' projecting from the other bar 22. The side-bars 21, 22 occupy a position beneath the main table-leaves 7, 7, and are supported, at their lower ends, on the upper surface of the members 3, 3, on which said side-bars slide, and are guided in their movement by the strips 6, 6 and a ledge 1^b of the side-bar 1; and are connected by vertical end-bars 24, 24, which, in the closed or retracted position of the sliding frame or carriage (as shown in Fig. 3), bear against the connecting bars 4, 4.

45 The sliding-carriages carry two arms 25, 25 which project from the side-bars 21, 22, each of said arms constituting a support for one end of a rod 26, the other end of which is supported in the adjacent end-bar 24.

50 Straps 27, loosely encircling the rod 26 and carried by the leaf-section 18 toward the hinge-end thereof, constitute the means for pivotally and slidably supporting the swinging leaf-sections 18, 19 on the rod 26. The 55 outermost strap 27 by contacting with the bar 24 limits movement in one direction of the sliding end-leaf 18—19, while the arm 25 by being contacted by the innermost strap 27 limits movement of said end-leaf in the opposite direction. Stop-pins 28, 28 carried by the end-bars 24, 24 limit downward-swinging movement of the leaf-sections 18—19, in the collapsed position thereof.

Horizontally-swinging latches or catches 65 7^c, 7^c, pivoted at one end thereof, as at 7^a, to

the under surface of the main table-leaves 7, 7 near the outer edges thereof, may be swung beneath the table-leaf sections 18—19, at the hinge portion thereof, so as to maintain said sections in the same horizontal 70 plane, as shown in Figs. 1 and 2. Also, hooks 7^c, pivoted at one end thereof, as at 7^c, to the under surface of the main table-leaves 7, 7, near the outer edges thereof, are adapted to engage pins 7^h carried by the supplemental 75 end table-leaves 18—19, when the said leaves are in operative position, as shown in Figs. 1 and 2, to hold them against separation from the main table-leaves 7, 7. Additional hooks 7^k carried by one of the main table-leaves 7 80 are adapted to engage pins 7^m carried by the other leaf 7, to hold said leaves together against accidental separation, when the supplemental table leaves are in collapsed position, as shown in Fig. 3.

85 A cover-plate 50 may be secured to the bottom of the members 3, 3 and 4, 4, if desired, to hide the interior mechanism of the table.

The operation of the device is as follows: In the position of the table wherein all the 90 supplemental leaves are in use, as shown in Figs. 1 and 2, the ends of the supplemental leaves 18—19, 18—19 are supported, against collapse, upon the tops of the end-bars 24, 24 and of the sliding side-bars 21—22, 95 21—22 of the sliding carriages, and are locked against collapse by pins 30 carried by the side edges of the main table-leaves 7, 7 engaging corresponding openings in the sides of the supplemental end leaves 18—19, 100 18—19, and by the catches 7^c carried by the main leaves 7, 7 being swung beneath the hinge-ends of said end supplemental leaves. The two sliding main leaves 7, 7 are supported partly upon the tops of the side-bars 105 1, 1 and partly upon the tops of the sliding side-bars 21—22, 21—22. The two intermediate supplemental leaves 15—16, 15—16 are supported upon the tops of the side-bars 1, 1, and, in the operative position thereof, are 110 locked against collapse by their pins 30 engaging corresponding recesses in the edge of the main leaves 7, 7, and by the catches 7^a, 7^a carried by the main leaves 7, 7. To collapse the supplemental leaves, so as to 115 bring the table to the position shown in Fig. 3, the table top is pulled, at each end, so as to separate or disengage the pins 30 in the sides of the leaves from engagement with the corresponding openings in the sides of 120 adjacent table-leaves, and the catches 7^a, 7^a are then disengaged. Each section 16 of the two center supplemental leaves is then swung upward, in the direction indicated by the arrow at the left in Fig. 6, onto the 125 section 15; then the two sections 15, 16 are swung in the reverse direction, or in the direction indicated by the arrow at the right in Fig. 6, so that the two superposed sections 15, 16 will occupy a position, as shown 130

in dotted lines in Fig. 6, beneath the table-top. In this position, the two sections will occupy an inclined position, with their lower ends supported upon the upper surface of the cover-plate 50, or, if the latter is not used, downward movement of the sections 15, 16 will be limited by the bar or brace 5. The operator then pushes against the side bars 24, 24 of the extensible traveling carriages which carry the end supplemental leaves 18—19, 18—19, so as to move said carriages toward each other and bring the two main leaves 7, 7 toward each other, to partly close the opening previously occupied by the supplemental leaves 15—16, 15—16 before they were swung down from the full-line position to the dotted line position thereof shown in Fig. 6. As the sliding-carriages are moved, as described, the end supplemental leaves 18—19, 18—19 push against and move the main leaves 7, 7 toward each other, to partly close the opening previously occupied by the supplemental leaves, as described. In such position of the carriages, the end supplemental leaves may be pushed inward, so as to remove them from support by the end bars 24, 24. The catches 7^c and the hooks 7^e are then disengaged, the sections 18 of said supplemental end leaves are then swung upward in the direction indicated by the arrow at the left in Fig. 4, so that the two sections lie one on top of each other. As the sections 18 are swung upward, as described, on their pivots 26, the inner or hinged end of said sections move downward, as shown in dotted lines in Fig. 5, which pulls the sections 19 in the direction indicated by the two arrows at the right in Fig. 5, whereby, in the collapsed position of said end supplemental

leaves, they occupy a position as shown in full lines in Fig. 5, downward movement being limited by the stops 28. The end bars 24, 24 are then pushed so as to move the traveling carriages toward each other a little more, thereby entirely closing the opening previously occupied by the center supplemental leaves 15, 16, 15, 16. The table is now in the contracted position shown in Fig. 3, and the hooks 7^k carried by one of the main table-leaves 7 are engaged with the pins 7^m carried by the other main leaf, so as to lock the table-leaves against accidental separation.

Having thus fully described my invention, what I claim as new and desire to secure by Letters Patent of the United States is:

In an extension table, two slidable main table-leaves, horizontally-slidable, supplemental table-leaves foldable and movable from a position between and in the same horizontal plane as the main leaves to a position beneath each of the same, two sliding carriages disposed beneath said main leaves, two supplemental, foldable end leaves supportable, in unfolded position, upon the tops of said carriages, two rods carried, at one end thereof, by said carriages, upon which said supplemental leaves are pivotally and horizontally-slidably mounted, and brackets carried by said carriages and secured, at their free ends, to the other ends of said rods.

In testimony whereof, I affix my signature in the presence of two witnesses.

GIUSEPPE BELLUSCI.

Witnesses:

WALTER S. ZACHARY,
FRANK S. PALADINI.
